GLASS STOPPER AND BOTTLE GRINDING
MACHINE

James H. Roberts and Charles V. Achauer, Zanesville, Ohio, assignors to Hazel-Atlas Glass Company, Wheeling, W. Va., a corporation of West Virginia

Application August 26, 1936, Serial No. 98,000

9 Claims. (Cl. 51—26)

The invention relates to a machine for automatically grinding together bottle stoppers and bottle necks, to assure an exact fit. One of the objects of the invention is to provide a machine which will automatically and efficiently grind 5 the stoppers and necks with great rapidity and accuracy.

Another object of the invention is to provide such a machine in which further grinding action 10 will be automatically stopped when the neck and stopper have been ground to the desired fit.

A further object of the invention is to provide improved means for applying abrasive material to the stopper, preferably at each reciprocation of the parts.

Still another object of the invention is to provide improved means for releasing the stopper and bottle when the grinding operation is completed.

20 Numerous other objects and advantages of the invention will be apparent to those skilled in the art, from the following detailed description, when taken in connection with the accompanying drawings, in which,

25 Figure 1 is a side elevational view of the machine.

Figure 2 is a detail elevational view of the trigger locking mechanism, in locked position.

Figure 3 is a plan view of the machine.

30 Figure 4 is a detail sectional view of the stopper gripping mechanism.

Figure 5 is a detail end view of the gripper jaws.

Figure 6 is a horizontal sectional view taken 35 on line 6—6 of Figure 1.

Figure 7 is a horizontal sectional view taken on line 7—7 of Figure 1.

Figure 8 is a vertical transverse sectional view of the bottle slide, taken on line 8—8 of Figure 1.

40 Figure 9 is a detail view of the mechanism for moving the bottle slide to a position to release the bottle, taken on line 9—9 of Figure 7, and

Figure 10 is a detail elevational view, parts being in section, of the mechanism for applying the 45 abrasive to the stopper.

Referring to the drawings in more detail, numeral 1 indicates a motor which, by means of sprocket chain 2, continuously rotates a shaft 3 mounted on table 4. Fixed to this shaft is a mitre gear 5 in mesh with a gear 6 fixed to a shaft 7 extending longitudinally of the table, and mounted in bearings 8.

The continuously revolving shaft 7 carries a 50 friction disc 9 which is intermittently engaged

by a friction disc 10 slidably mounted on and rotatable with the stopper spindle 11. When these friction discs are engaged the spindle is rotated to rotate the glass stopper carried thereby.

The preferred means for mounting the stopper on the spindle, will now be described. Numeral 12 refers to a collar attached to the spindle 11 by means of a set screw 13. Numeral 14 indicates two gripper jaws which have their rear 10 ends removably attached to the collar, and their forward ends normally urged apart by means of springs 15. The stopper 16, which is to be ground, is gripped between these jaws.

Numeral 17 refers to a cylindrical sleeve which 15 is slidably keyed to the spindle 11, and which is normally urged into telescopic relation over the clamping jaws 14, by means of coil spring 18. This movement of the sleeve in cooperation with the tapered walls of the clamping jaws, brings 20 the jaws together to grip the stopper 16. To assemble the clamping device the sleeve is moved to the left (Fig. 4) against spring 18, to expose the collar 12. The grooves in the rear ends 25 of the jaws are then placed over a tongue provided on the collar 12, and the sleeve is then released and is moved to telescopic relation with the jaws by means of the spring 18. To release the stopper after it has been ground only a slight movement of the sleeve to the left (Fig. 4) 30 is necessary, whereupon the springs 15 will separate the jaws to release the stopper. The means for moving the sleeve to release the stopper, and the means for stopping the rotation of the spindle 35 11, will now be described.

Numeral 19 refers to a foot-treadle which is connected to a lever 20 by means of a link 21, so that when the foot-treadle is depressed the upper arm of the lever 20 will be moved to the left (Fig. 1); the lever being normally moved in the 40 opposite direction by coil spring 22, to maintain the foot-treadle in elevated position.

The upper arm of the lever 20 is connected by means of a link 23, with one arm of a lever 24; the other arm of the lever 24 being connected 45 with a collar 25 attached to the friction disc 10. Thus when the foot-treadle is depressed the friction clutch is thrown out, thereby breaking the connection between the stopper spindle and its driving mechanism.

The depression of the foot-treadle also releases the stopper. Attached to the upper arm of lever 20 is a link 26, which link has its opposite end connected to a lever 27 fulcrumed at 28. The forward end of this lever engages a collar 29 pro- 50 55

vided on the clamping sleeve 17. So that when the upper end of lever 20 is moved to the left by the depression of the foot lever, the clamping sleeve 17 will also be moved to the left (Fig. 3), thereby releasing the clamping jaws and permitting them to be separated by the springs 15, to release the stopper. Another stopper is now placed between the jaws and the foot-treadle released, whereupon the spring 22 will move the lever 20 in the opposite direction, thereby clamping the stopper in place and throwing in the friction clutch to cause rotation of the stopper spindle 11. While we have illustrated only a single stopper spindle, it will of course be understood that any desired number of these spindles may be arranged in series, be driven from the shaft 3, and the several spindles tended by the same operator.

The mechanism for holding the bottle to be ground with the stopper, and for reciprocating the bottle toward and from the stopper, will now be described. Numeral 30 refers to the bottom plate of a slide adapted to be reciprocated on tracks 31 extending from the table 4. Four studs 32 extend upwardly from the bottom plate and mounted thereon is the upper plate 33 of the slide or carriage. Springs 34 are mounted on the studs between the bottom and top plates, and nuts 35 are threaded on the upper ends of the studs. Thus by adjusting these nuts the upper plate, which carries the bottle to be ground, can be vertically adjusted to align the bottle neck with the stopper.

Numeral 36 refers to a pad or wood block mounted in the upper plate of the slide. Different blocks are used for bottles of different shapes and sizes; the block being dished out to receive with a snug fit a bottle 37 of a particular size and shape. By reference to Figure 3 it will be noted that the block or pad 36 is of somewhat less width than the distance between the side walls of the upper plate 33. Thumb screws 38 mounted in the slide engage the sides of the block, and by adjusting these thumb screws the block can be accurately adjusted laterally. The block can also be adjusted vertically in the upper slide or carriage by means of shims 39 (Fig. 8).

The bottle slide is reciprocated by means of a cam 40 fixed to a continuously rotating shaft 41. This shaft is provided at one end with a worm wheel 42 engaged by a worm 43 on a shaft 44. The opposite end of the shaft 44 carries a mitre gear 45 meshing with a similar gear 46 on the shaft 3, whereby the continuous rotation of the shaft 3 causes the continuous rotation of the shaft 41. Numeral 47 refers to a lever fulcrumed on a rod 48 and adapted to be engaged by the cam 40. This lever 47 is connected by a link 49 with a lug 50 fixed to and projecting downwardly from the bottle slide 30. Thus the movement of the cam 40 will cause the bottle slide to be moved away from the stopper, and as the cam recedes a coil spring 51, having its ends connected to the slide and to the table 4, will cause the slide to move toward the stopper, bringing the bottle and stopper into grinding relation. During this reciprocation of the bottle slide, the bottle 37 is secured in the block or pad 36 by means of a clamp 52 attached to arms 53 which are pivotally mounted at 54 on the upper plate 33 of the slide. The clamp is normally held in engagement with the bottle by means of a coil spring 55. The arms 53 extend below their pivots 54, and when the grinding has been completed 75 and the slide is moved backwardly to release the

bottle, in a manner to be later described, the arms 53 engage pins 56, thereby lifting the clamp from the bottle.

The above-described reciprocation of the bottle slide continues until the bottle and stopper have been sufficiently ground, and further reciprocation of the slide is then automatically stopped, by mechanism now to be described. Numeral 57 refers to a finger mounted on the bottle carriage to reciprocate therewith, and projecting downwardly therefrom. A trigger 58 in the form of a bell-crank lever is pivotally mounted at 59, upon a bracket 60 extending from the table 4. This trigger 58 is adapted to assume two positions; the first or inoperative position being illustrated by Figure 1, and the second or operative position being illustrated by Figure 2. The trigger is retained in either of its two positions by means of a coil spring 61 having one end attached to an arm 62 extending downwardly from the bracket 60, and its other end attached to a cross-bar 63 extending between the two arms of the bell-crank lever 58. When the bell-crank lever is in its inoperative position (Fig. 1) it is abutting against an adjustable screw 64 and is maintained in that position by the spring 61; and when the lever is moved slightly to the left, the spring snaps it over into operative position.

When the trigger is in its inoperative position, the bottle carriage is free to reciprocate back and forth, to bring the bottle and stopper into and out of grinding relation, without the finger 57 engaging a bolt 65, threadedly mounted for adjustment in the bell-crank lever. But when the grinding has continued to the extent desired the movement of the carriage will be such that the finger 57 will engage the bolt 65 to thereby slightly move the trigger to the left, whereupon the spring 61 will snap the trigger into its operative position. Then as the carriage moves back the finger 57 will ride over the upper end of the arm 66 of the bell-crank lever, and it will spring upwardly into the notch 67 provided at the lower end of finger 57, and further forward movement of the carriage is prevented by reason of the arm 66 engaging the abrupt shoulder 68 on the finger 57; it being understood of course, that the cam 40 which reciprocates the bottle carriage continues its rotation, but it is no longer effective in reciprocating the carriage.

The grinding of the bottle and stopper has been completed, and the bottle carriage has been locked in inoperative position. The bottle is now released by the mechanism to be described. Attached to the previously described foot-treadle 19 is a link 69 which has its other end connected to arm 70 of bell-crank lever 71 fulcrumed on the rod 48. The other arm 72 is pivotally attached to a hollow cylindrical member 73 which is closed at its rear end, but open at its forward end to telescopically receive a connecting rod 74. This connecting rod is freely slidable in the cylinder, and its opposite end is connected to the lug 50 which projects downwardly from the bottom of the bottle slide or carriage.

When the bottle carriage is reciprocated back and forth in the normal operation of grinding the bottle and stopper, the rod 74 merely slides back and forth in the cylinder; the end of the rod almost but not quite reaching the closed end of the cylinder. When the grinding operation has been completed and the reciprocating movement of the carriage has been automatically stopped, the foot-treadle is depressed thereby moving the cylinder 73 to the right (Fig. 9), whereupon the

closed end of the cylinder engages the end of the connecting rod 74 and moves the carriage rearwardly. As the carriage is thus moved rearwardly the arms 53 of the bottle clamp 52 engage the pins 56, thereby lifting the clamp and releasing the bottle. Counterweight 75, adjustably attached to the bell-crank lever moves the carriage back to operative position when the foot-treadle is released. The above-described rearward movement of the bottle carriage also causes the finger 57 to ride over the arm 66 of the trigger mechanism, pushing it slightly to the right, whereupon the spring 62 snaps it into inoperative position against the screw 64, thereby permitting normal operation of the bottle carriage when the foot-treadle is raised.

Thus the depression of the foot-treadle releases the ground bottle and resets the trigger; and, as hereinbefore described the depression of this foot-treadle at the same time releases the bottle stopper and throws out the friction clutch. Another stopper and bottle are now inserted, the foot-treadle is released, and the grinding is resumed. As stated above the foot-treadle is ordinarily depressed after the reciprocation of the bottle carriage has been automatically stopped; but it will be apparent that the foot-treadle may be depressed at any time, without regard to the automatic stop mechanism, whereupon it will perform the same operations as described above. Thus the operator has complete control over the machine at all times.

We have described the construction and operation of the complete mechanism for grinding the bottles and stoppers, and we shall now describe the mechanism for applying the abrasive material to the stopper, preferably at each reciprocation of the bottle carriage. Numeral 76 refers to a mitre gear keyed to the shaft 41 and meshing with a similar gear 77 keyed to a vertical shaft 78, whereby the vertical shaft is continuously rotated. Mounted on the upper end of this shaft 78 is a crank arm 79 which is connected, by means of a link 80, with one arm of a lever 81 fulcrumed at 82 on the table 4. The other arm of the lever 81 has the abrasive-applying brush 83 mounted thereon, in a manner to permit the brush to be raised and lowered. In the specific construction illustrated numeral 84 indicates a plate held in place on the lever 81 by means of the pins 85 and 86. The pin 85 has a spring 87 mounted thereon to normally hold the plate down against the lever, and the pin 86 prevents the plate from moving to either side yet permits it to have free movement in an upward direction by reason of the elongated opening 88.

The forward end of the plate 84 has a downwardly extending flange 89, upon which the abrasive-applying brush 83 is mounted. Numeral 90 refers to an abrasive container, and the brush is shown in Fig. 10 in lowered position in the abrasive material. In applying the abrasive material to the stopper the brush is lifted from the container as it moves toward the stopper, and after clearing the container it is lowered to bring it into engagement with the stopper; and on the return trip the brush is raised as it approaches the container and then lowered when it is over the container. To accomplish this movement we provided an arcuate cam track having a low portion 91 and a hump portion 92; and a roller 93 carried by the downwardly extending flange 89 rides on the arcuate cam track. Assuming the parts are in the positions shown in Figures 3 and 10, with the roller 93 on the low portion 91 of the cam and the

brush submerged in the abrasive material, then the continued rotation of the crank arm 79 causes the lever 81 to be swung toward the stopper 16. When this travel starts the roller 93 rides up on the hump 92 to lift the brush clear of the container, and as the movement continues the roller rides down off the hump thereby lowering the brush so that it will, upon further movement, engage the stopper and apply the abrasive thereto. The continued rotation of the crank causes the reverse movement of the brush, so that as it approaches the container it is elevated by the roller engaging the hump, and as the movement continues the roller rides down the hump onto the low portion 91 of the cam, to lower the brush into the abrasive material.

As will be apparent from the construction illustrated and described, the brush makes one complete oscillation every time the bottle carriage makes a complete reciprocation, and of course the parts are synchronized so that the brush applies the abrasive material to the stopper while the bottle is clear of the stopper.

The operation of the machine has been described in connection with the description of the construction, and will be clearly understood without further description. It will be apparent that we have devised a completely automatic machine which will rapidly and accurately grind together glass stoppers and bottle necks; that the forward movement of the bottle into engagement with the stopper is caused by a spring action, whereby the bottle is gradually moved farther and farther upon the stopper as the grinding proceeds; that further reciprocation of the bottle is automatically prevented after the grinding has proceeded to the desired extent; that abrasive material is periodically applied to the stopper; and that the release of the bottle, the release of the stopper, and the stopping of the stopper spindle rotation are all accomplished by the depression of a single foot-treadle.

While we have described in detail the preferred construction of the machine, yet it is to be understood that many changes and modifications may be made in the construction without departing from the spirit of the invention, and all such changes and modifications are intended to be included within the scope of the claims. Also, as previously mentioned, any desired number of stopper spindles and associated parts may be arranged side by side, be operated from the single driving shaft, and be tended by the same operator.

What we claim is:

1. A machine for grinding together glass bottle necks and stoppers, including means for holding a stopper, means for holding a bottle, means for rotating one of the articles, means for periodically moving one of the articles into and out of grinding relation with the other article, and mechanism for automatically stopping such periodic movement when the stopper has reached a predetermined seating position in the bottle neck.

2. A machine for grinding together bottle necks and stoppers, including means for holding a stopper, means for holding a bottle, means for rotating one of the articles, means for periodically moving one of the articles into and out of grinding relation with the other article, an abrasive-applying brush, and means for moving the brush over the stopper each time the articles are separated.

3. A machine for grinding together bottle necks and stoppers, including means for holding a stop-

per, means for holding a bottle, means for rotating one of the articles, means for periodically separating the bottle and stopper, spring means or the like for periodically bringing the bottle and stopper into grinding relation, whereby the extent of movement toward each other is gradually increased as the grinding action proceeds, an abrasive-applying brush, an abrasive container, and means for periodically moving the brush from the container to the stopper.

4. A machine for grinding together bottle necks and stoppers, including means for holding a stopper, means for holding a bottle, means for rotating one of the articles, means for periodically moving one of the articles into and out of grinding relation with the other article, mechanism for automatically stopping such periodic movement when the stopper has reached a predetermined seating position in the bottle neck, and means for applying abrasive material to one of the articles.

5. A machine for grinding together bottle necks and stoppers, including means for holding a stopper, means for holding a bottle, means for rotating one of the articles, means for periodically separating the bottle and stopper, spring means or the like for periodically bringing the bottle and stopper into grinding relation, whereby the extent of movement toward each other is gradually increased as the grinding action proceeds, and mechanism for automatically stopping such periodic movement when the stopper has reached a predetermined seating position in the bottle neck.

35. 6. A machine for grinding together bottle necks and stoppers, including means for holding a stopper, means for holding a bottle, means for rotating one of the articles, means for periodically

5
cally moving one of the articles into and out of grinding relation with the other article, mechanism for automatically stopping such periodic movement when the stopper has reached a predetermined seating position in the bottle neck, and manually operated means for stopping such periodic movement at any time.

7. A machine for grinding together bottle necks and stoppers, including means for holding a stopper, means for holding a bottle, means for rotating one of the articles, means for periodically moving one of the articles into and out of grinding relation with the other article, means for automatically stopping such periodic movement when the stopper has reached a predetermined seating position in the bottle neck, and means for simultaneously releasing both articles.
